DESIGN FOR A GLASS JAR

William J. Lundy, Olean, N. Y., assignor to Olean
Glass Company, Olean, N. Y., a corporation of
New York

Application July 22, 1941, Serial No. 102,364

Term of patent 14 years

To all whom it may concern:

Be it known that I, William J. Lundy, a citizen of the United States and residing at Olean, in the county of Cattaraugus and State of New York, U. S. A., have invented a new, original, and ornamental Design for a Glass Jar, of which the following is a specification, reference being had to the accompanying drawing, forming a part hereof, wherein:

Figure 1 is a side elevational view of a glass jar embodying my new design;

Figure 2 is a sectional view taken on the line II—III of Figure 1; and

Figure 3 is a bottom plan view thereof.

I claim:

The ornamental design for a glass jar, substantially as shown.

WILLIAM J. LUNDY.
